CONTAINER FOR MELTING AND POURING
PARAFFINEvelyn D. L. Huff and Helen K. Olson,
Mandan, N. Dak.

Application September 15, 1938, Serial No. 230,148

3 Claims.

(Cl. 53—1)

This invention relates to a container especially adapted for use in connection with paraffin or any equivalent wax or substance and it aims to provide a novel structure in which the wax is adapted to be melted and from which it is adapted to be poured, particularly for canning purposes, or any other. The structure is also adapted to contain wax when it is not being used for melting and pouring purposes.

10 A particular object is to provide a structure wherein the solid paraffin cannot clog the dispensing openings or seriously interfere with the pouring operation.

15 The more specific objects and advantages will in part be pointed out and otherwise become apparent from a consideration of the description following taken in connection with accompanying drawing illustrating one operative embodiment by way of example.

20 In said drawing.

Figure 1 is a view partly in side elevation and partly in section of the device constituting the invention;

25 Figure 2 is a horizontal sectional view taken on the line 2—2 of Figure 1, and

Figure 3 is a fragmentary elevation, partly broken away and in section, looking toward the pouring spout.

Referring specifically to the drawing wherein like reference characters designate like or similar parts, the container has a body 10, preferably metallic, of any desired size and shape, preferably square in cross section with the corners rounded as suggested at 11. Such container or body is open at the top but has a bottom 12, preferably much thicker than the wall of the container in order to add weight to prevent the container from tipping and also in order to retain heat.

40 The paraffin or other material is placed in the container 10 and need never be removed from it because it is sanitary for storing. However, the paraffin or material is adapted to be melted while in the container, the bottom 12 being disposed over a suitable flame. The molten paraffin is poured from the container in a thin stream, through the dispensing openings 13, into a spout 14 fastened to the exterior of the container, the spout being preferably V-shape in cross section and constructed and arranged to pour a thin stream.

45 Difficulty has been experienced heretofore in not being able to pour molten paraffin satisfactorily because the solid paraffin would move too close to the openings 13 and oftentimes seal or

5 clog them enough to prevent the passage of the paraffin. To avoid such a condition, pegs or projections 15 are fastened removably or permanently in certain of the openings 13, projecting interiorly of the container and serving as abutments for solid paraffin, thus preventing the solid paraffin from directly contacting with the metal of the container 10 adjacent openings 13, thus always leaving a channel or space beneath the same for escape of the paraffin to and through 10 the openings 13 and spout 14.

15 A cover 16 is removably telescoped over the exterior of the container 10, preferably fitting rather tight, although removable. Since the cover fits exteriorly, danger of the sealing there- 15 of to the container by molten paraffin is overcome.

20 A handle 17 is provided on the container and a handle 18 is provided on the cover 16. These handles are preferably metallic so as to be fire- 20 proof and quick cooling and each is rolled from a flat piece of metal, which is irregularly shaped as at 19, in order to fit the hand and give a more secure grip.

25 The relatively heavy bottom 12 protects the 25 paraffin from too intense heat as well as serving to retain heat longer.

30 Various changes may be resorted to provided they fall within the spirit and scope of the invention.

We claim as our invention:

1. A receptacle for containing, melting and pouring paraffin or the like, said receptacle comprising a container, the container having discharge openings in a wall thereof, and a plurality of spaced peg-like elements extending inwardly from the interior of the wall of the container having distal inner ends adjacent said openings with said distal inner ends directly exposed to the contents of the receptacle for contact with solid paraffin to prevent interference of the latter with the discharge of molten paraffin through said openings.

2. A receptacle for containing, melting and pouring paraffin or the like, said receptacle comprising a container, discharge openings in the container, means extending inwardly from the interior of the wall of the container to prevent interference of solid paraffin with the discharge of molten paraffin through said openings, said projections consisting of elements removably disposed in certain of said openings.

3. A receptacle for containing, melting and pouring paraffin or the like, said receptacle comprising a container, discharge openings in the 55

container, means extending inwardly from the interior of the wall of the container to prevent interference of solid paraffin with the discharge of molten paraffin through said openings, said projections consisting of elements removably disposed in certain of said openings, said elements

having heads disposed exteriorly of the container and reduced portions extending through certain openings and beyond the same.

HELEN K. OLSON.
